CHIPPING HAMMER

Eugene M. McMurtry, Denver, Colo.

Application September 18, 1945, Serial No. 617,051

5 Claims. (CL 125—33)

1

My invention relates generally to improvements in chipping hammers and the like tools, and more particularly to such a tool having an improved sleeve in which the hexagonal or semi-circular cross section bit or chisel works, the said sleeve being capable of freely revolving in the hammer casing or of being locked in any one of a number of different rotary positions, whereby the same tool can be utilized for difficult types of work without the operator's changing the usual holding position of the tool, the primary object of the invention being to provide an arrangement whereby the functions of two tools, the one having a stationary hexagonal bore sleeve in which the bit cannot turn and the other having a cylindrical bore sleeve in which the bit is free to turn, are made accessible in a single tool.

Other important objects and advantages of the invention will be apparent from a reading of the following description and the appended drawings showing a preferred embodiment of the invention for illustration only.

In the drawings:

Figure 1 is a general side elevation and longitudinal sectional view taken through a chipping hammer constructed according to the present invention.

Figure 2 is a bottom plan view of the flanged sleeve showing the positioning holes therein.

Figure 3 is a bottom plan view of the locking nut.

Figure 4 is a side elevation of the locking nut in inverted position.

Referring in detail to the drawings, the numeral 5 generally designates the chipping hammer casing or barrel having the cylindrical liner 6 adjacent to its lower end, conformably and rotatably receiving the sleeve 7 which has a non-circular bore 8, hexagonal in the illustrated form, to slidably and non-rotatably accommodate the chisel or bit 9.

The sleeve 7 terminates at its lower end in a circular flange 9' smaller in diameter than the interior of the barrel 5 below the liner 6, as shown in Figure 1, and provided at selected or equal circumferential intervals with positioning holes 10.

Holding the sleeve 7 in place in the lower end of the barrel 5 is the locking nut 11 which includes the exteriorly threaded cylindrical section 12 which threads into the lower end of the barrel 5 to hold the sleeve flange 9' against the lower end of the liner, and the wrench accommodating portion 13 on its lower side or end. A

smooth circular bore 14 is provided in the nut to freely pass the chisel or bit 9.

At one side the nut 11 has two bores 15 and 16 arranged substantially parallel to the axis of the nut and connected by a communicating recess 17, in which is pivoted at 18 a lever 19 which extends into both of the bores 15 and 16 and is pivoted therein to the detent pin 20 in the bore 15 and the push pin 21 in the bore 16. The bore 15 is formed through the top of the nut to permit the detent pin 20 to extend above it and into any one of the positioning holes 10 in the flange of the sleeve 7 and thereby lock the sleeve against rotation in a selected position of rotary adjustment. When the detent pin 20 is withdrawn flush with the top of the nut 11 the sleeve 7 is free to turn in the hammer barrel so that the chisel or bit 9 is then free to turn relative to the barrel.

When the detent pin 20 is in the elevated locking position illustrated in Figure 1 the push pin 21 is in the depressed position shown and depends sufficiently below the nut to enable it to be pushed upwardly far enough to withdraw the detent pin from locking position when it is desired that the chisel turn freely relative to the hammer barrel. In the illustrated arrangement a spring detent 22 is provided in the bore 16 to releasably engage a notch 23 in the side of the push pin 21 to hold the latter in elevated position and consequently the detent pin 20 in non-locking position.

The barrel 5, liner 6, sleeve 7 and tool 9 fit one another with some degree of tightness, so that while permitting some adjustment by rotation, the parts will be held more or less tightly together against axial displacement. The tool 9 will be held in place against projection by the hammer upon striking the same by virtue of the tool being upon the work. The blows of the hammer will merely depress the same against the work. The movement of the hammer being limited at the most, the tool 9 would only be extended to a short distance out of range of the hammer.

I claim:

1. A chipping hammer or the like comprising a barrel including a liner adjacent to its outer end formed with a cylindrical bore, a sleeve having a cylindrical portion rotatably inserted in said cylindrical bore and having a flange to engage the outer end of said liner within said bore, said sleeve having a non-cylindrical bore, a reciprocable bit of a cross section non-rotatably and slidably fitting in the sleeve bore, an annular nut threaded on the outer end of said barrel through which the bit freely passes, said nut having a portion engaging the outer side of the sleeve

flange to hold the flange against the outer end of the liner, said flange being formed with circumferentially distributed positioning apertures, and releasable detent means on said nut for lockably engaging any of said apertures to lock the sleeve in a selected rotary position relative to the barrel.

2. A chipping hammer or the like comprising a barrel including a liner adjacent to its outer end formed with a cylindrical bore, a sleeve having a cylindrical portion rotatably inserted in said cylindrical bore and having a flange to engage the outer end of said liner within said bore, said sleeve having a non-cylindrical bore, a reciprocable bit of a cross section non-rotatably and slidably fitting in the sleeve bore, an annular nut threaded on the outer end of said barrel through which the bit freely passes, said nut having a portion engaging the outer side of the sleeve flange to hold the flange against the outer end of the liner, said flange being formed with circumferentially distributed positioning apertures, and releasable detent means on said nut for lockably engaging any of said apertures to lock the sleeve in a selected rotary position relative to the barrel, and means on said nut for releasably holding said detent means in non-locking position permitting the sleeve and the bit to rotate freely relative to the barrel.

3. In a chipping hammer the like of the type having a barrel including a liner formed with a cylindrical bore, a sleeve rotatable in said liner bore and provided with a non-cylindrical bore for non-rotatably accommodating a reciprocating non-cylindrical bit, and an annular nut threaded on the end of the barrel and freely passing the bit, said nut having a portion entering the end of the barrel and engaging a portion on said sleeve to position the sleeve in the liner, and releasable detent means on the nut for lockably engaging said portion of the sleeve enabling locking the sleeve and thereby the bit in a selected position of rotation relative to the barrel and confining the bit to reciprocation in such position.

4. A chipping hammer or the like comprising a barrel including a liner adjacent to its outer end formed with a cylindrical bore, a sleeve having a cylindrical portion rotatably inserted in said cylindrical bore and having a flange to engage the outer end of said liner within said bore, said

sleeve having a non-cylindrical bore, a reciprocable bit of a cross section non-rotatably and slidably fitting in the sleeve bore, an annular nut threaded on the outer end of said barrel through which the bit freely passes, said nut having a portion engaging the outer side of the sleeve flange to hold the flange against the outer end of the liner, said flange being formed with circumferentially distributed positioning apertures, and releasable detent means on said nut for lockably engaging any of said apertures to lock the sleeve in a selected rotary position relative to the barrel, said detent means comprising a detent pin movable into and out of locking position, a push pin, and a pivoted element operatively connecting the detent pin and the push pin.

5. A chipping hammer or the like comprising a barrel including a liner adjacent to its outer end formed with a cylindrical bore, a sleeve having a cylindrical portion rotatably inserted in said cylindrical bore and having a flange to engage the outer end of said liner within said bore, said sleeve having a non-cylindrical bore, a reciprocable bit of a cross section non-rotatably and slidably fitting in the sleeve bore, an annular nut threaded on the outer end of said barrel through which the bit freely passes, said nut having a portion engaging the outer side of the sleeve flange to hold the flange against the outer end of the liner, said flange being formed with circumferentially distributed positioning apertures, releasable detent means on said nut for lockably engaging any of said apertures to lock the sleeve in a selected rotary position relative to the barrel, said detent means comprising a detent pin movable into and out of locking position, a push pin, a pivoted element operatively connecting the detent pin and the push pin, and a releasable spring detent engageable with the push pin to releasably hold the push pin and the detent pin in non-locking position.
